UNITED STATES PATENT OFFICE.

LOUIS SCHUTTE, OF PHILADELPHIA, PENNSYLVANIA.

INJECTOR.

SPECIFICATION forming part of Letters Patent No. 276,898, dated May 1, 1883.

Application filed February 17, 1883. (Model.)

To all whom it may concern:

Be it known that I, LOUIS SCHUTTE, of Philadelphia, in the county of Philadelphia and State of Pennsylvania, have invented certain 5 Improvements in Steam-Jet Injectors, &c., of which the following is a specification.

My present invention relates to starting and relief valves on injectors and other steam-jet apparatus for the forcing of liquids and fluids, 10 and more particularly those that may be subjected to sudden counter-pressure exceeding the nominal counter-pressure which they have been constructed to overcome.

The accompanying drawings illustrate an 15 injector or steam-jet apparatus of simple form having my improvements embodied therein.

Figure 1 is a longitudinal section of the apparatus and valve attached. Fig. 2 represents a cross-section on the center-line $x-x$ of the 20 valve, showing the valve-seat, discharge, and overflow passage. Fig. 3 shows an elevation, partly in section, of the apparatus in a modified form. With reference to Figs. 1 and 2, I will explain its action.

25 The principal parts of the apparatus are the steam-nozzle A, combining-tube B, delivery-tube C, steam-inlet D, water-inlet E, and discharge F, all of substantially the usual form and arrangement.

30 G is the starting and relief valve, which, with its connections, forms the subject of the present invention. The valve G, opening from the discharge F of the instrument outward, carries on its outer end a piston, H, working 35 in a cylinder, and beyond this a stem, I, with a washer and nut, against which a spring, K, acts upward, so that if no other influence is brought to bear on the valve the action of this spring will cause it to be kept open. If, however, sufficient pressure is applied on top of the piston H, the valve will close against the pressure from the discharge-pipe F, exerted against the under side of the valve G. The 40 space above the valve and below the piston communicates with the waste or overflow passage L. By applying on top of piston H the same steam-pressure as that under which the injector or steam-jet apparatus is operated, and by properly proportioning the area of the 45 piston H and the valve G, the valve can be

made to open as soon as the pressure in the discharge end of the instrument exceeds that bearing a fixed relation to the steam-pressure, and will remain closed or will close whenever it is lower than would be admissible as determined by the relation of areas and pressures. 55

Among cases where such an instrument will find useful application is that of feeding a nest of boilers where the admission to each boiler 60 can be regulated or closed separately, where it may occur that the discharge from the instrument may temporarily be greatly contracted or entirely closed, in which case the counter-pressure in the discharge will rise till it opens 65 the discharge-valve, and the instrument will continue to work, discharging through the passage L. Another case is that where the instrument is used as a fire-engine, where a bend or obstruction in the hose or a closing of 70 the discharge-nozzle may cause an excessive pressure, in which case the relief-valve will open and allow of a continuous working of the apparatus.

The operation of the valve is as follows: 75 The instrument is started in the usual manner through the valve G, which is kept open for the purpose. Steam being then admitted on top of piston H, it closes, and the instrument delivers through the discharge F. The turning on of the steam on the piston H can be made a separate action by operating a cock or valve by hand, or made automatic through connections with the main starting mechanism, as shown in the accompanying drawings. Referring to these connections, as shown in Fig. 1, M is a passage from the steam-supply, opening into a small steam-chamber, N, containing a slide-valve, O. P is a passage leading from beneath the slide-valve to the waste or overflow L. The slide-valve has its rod or stem connected to the operating-stem of the main steam-admission valve. 85 90

In the position of the parts shown in the drawings a communication is established from 95 above the piston H through passage P, underneath the slide-valve O, and through passage Q, with the waste-passage L, thereby relieving the piston H of pressure, and causing the valve to be kept open by the spring K. 100

The slide-valve O is made sufficiently long or the connection between it and the operating-stem of main valve has sufficient lost motion to admit of the main valve being opened sufficiently to bring the apparatus into action before a change in the communication from above the piston with the waste-passage is effected, while a further movement cuts off this communication and opens the passage P through 5 M with the steam-chamber, thereby placing a pressure on the piston and closing the valve G. In this way it will be seen that a ready starting of the instrument can be effected through the valve G at all times, while it acts 10 at the same time as a relief-valve in the event of the pressure of the discharge becoming higher in proportion to the governing steam-pressure than that limited by the proportionate areas of valve and piston.

15 Fig. 3, showing a modified form of the apparatus, will be readily understood. It has the leading parts for the same purpose as explained with regard to Fig. 1. In this case the valve G is placed below and connected with the piston H by means of a lever, R. The object of this modification is to reduce the area of the steam-piston H, which controls the opening and closing of the valve. The admission of steam on this piston is in this case effected 20 by a three-way cock or valve, O, which, when closed against the steam, communicates with the atmosphere, thereby relieving the pressure from under the piston. This starting and relief valve may be advantageously applied to 25 any form of steam-jet apparatus or injector, be it double tube, self-adjusting, or any other. A diaphragm may be substituted for the piston H. The valve may also be separate from the body of the injector, and simply connected thereto by pipes or other suitable means.

30 The present invention is restricted to those matters and things which are hereinafter claimed, and as to all matters which may be described or shown, but which are not claimed, 35 the right is reserved to make the same the subject of a separate application.

Having thus described my invention, what I claim is—

1. In a jet apparatus for the forcing of liquids or fluids, an overflow-valve, substantially as described, arranged to be acted upon on one side by the pressure of the discharge and on the other side by the pressure of the steam or fluid by which the apparatus is operated, whereby an excessive counter-pressure or resistance causes the automatic opening of the overflow-valve. 50

2. In a steam-jet apparatus, substantially such as shown, an overflow-valve communicating with the discharge end and subject to the pressure of the outgoing fluid, combined with a closing-piston having an area greater than that of the valve, and a conductor or passage whereby the pressure of the steam or actuating-fluid is applied to hold the overflow normally in a closed position. 60

3. In a steam-jet apparatus for moving fluids, a main valve for admitting the actuating-steam to the apparatus, an overflow and starting valve at the delivery end, a piston to close the overflow-valve, and a valve connected and arranged to admit steam behind the piston after the opening of the main valve, substantially as described, whereby the overflow-valve is relieved from the closing-pressure and permitted to remain open until after the apparatus has been set in action. 70

4. In a jet apparatus for moving fluids, the combination of the overflow-valve, the piston to close the same, the passages P Q, and the valve O, acting in connection with said passages and with the steam-supply. 80

5. In a steam-jet apparatus, an overflow relief-valve constructed and arranged, substantially as described, to receive upon its outer side a fluid-pressure in excess of the normal pressure of the fluid discharged by the apparatus. 85

6. In a jet apparatus of the character herein represented, the combination of the valve G, piston H, spring K, passages M P Q, and valve O. 90

LOUIS SCHUTTE.
